HANDLE CONSTRUCTION FOR DISPENSING VALVES

Benjamin Minovitz, Hyattsville, Md.

Application July 8, 1949, Serial No. 103,654

3 Claims. (Cl. 40—67)

1

This invention relates to a handle construction for dispensing valves such as are used in the sale of beer and like beverages.

By way of background, it may be noted that beer to be dispensed is maintained under a not inconsiderable amount of gaseous pressure, and as long as the keg from which the beer is being dispensed is not exhausted, said pressure will of course permit a glass of beer to be drawn in a normal manner.

However, upon exhaustion of the beer in a particular keg, the gas maintained under pressure will itself begin to move through the dispensing valve, mixed with droplets and other small quantities of such beer as remains. This is accompanied by a loud hissing sound, and the bartender is thus made immediately aware of the fact that the keg has "blown."

Throughout the trade, it is common practice, when this happens, to invert an ordinary glass and position it over the dispensing valve handle or knob. This, of course, is to provide the bartender and other persons working behind the bar with a reminder that no more beer should be drawn through the particular dispensing valve until a new keg is tapped, at which time the glass is removed.

The inverted glass is, of course, only a makeshift signal or flag, at best, and presents decided annoyance and inconvenience. For example, it is very common for the bartender to grasp, without thinking, the inverted glass time and again, on successive occasions when drawing glasses of beer.

It is an important object of the present invention, accordingly, to provide a dispensing valve handle construction which will eliminate the annoying and inconvenient practice which heretofore has had to be followed when a keg has "blown." It is a further object to provide a handle construction which will fulfill the purpose stated above, while yet normally presenting to the casual observer the same outward appearance as has heretofore been conventional.

Another object is to provide a handle as stated which, though equipped with a signal means for the purpose described, will nevertheless be fully capable of normal use during regular dispensing operations, the handle presenting no obstructions or mechanism which would interfere with the bartender's normal dispensing of a glass of beer.

Still another object is to provide a handle construction as stated wherein said signal means will be built in, in a manner which will not interfere with the necessary and obviously desirable brand marking customarily applied to said handle.

2

Still another object is to provide a device as stated which will be of simple construction and easy to use, so as to permit construction of the handle at little or no increase in cost above the cost of manufacturing handles that are not so equipped.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawing:

Fig. 1 is a side elevational view, part being shown in section, of one form of handle constructed in accordance with the invention.

Fig. 2 is a section on line 2—2 of Fig. 1, the dotted lines indicating positions of a flag member and movement thereof to operative position.

Fig. 3 is a bottom plan view of the handle.

Fig. 4 is a fragmentary exploded perspective view.

Referring to the drawing in detail, in the illustrated example of my invention, I have shown a dispensing valve handle which, as seen from Figs. 1 and 3, is outwardly of wholly conventional appearance and configuration. Such a handle or knob is commonly formed with a body 5 here illustrated as being of hemispherical shape and having rigid therewith the projecting stem 6 formed with threaded recess 7 for attachment of the knob or handle to the operating rod, not shown, of a conventional beer tap or dispensing valve, also not shown.

The body 5 is equipped with means, here shown as comprising a gripping flange 8 integral with said body, for mounting upon the body of a cover panel 9, the flange 8 in the present instance being crimped into gripping engagement with the periphery of said panel. Such a panel is conventionally lettered and/or pictorially illustrated to show the brand designation of the beer being drawn from the particular dispensing valve.

It is quite possible that the shape of the body 5 and of the panel 9, and the type of connecting means employed between the panel and body, might differ in one handle as compared to another. However, all handles of this type have in common the fact that they include a body which is an enlargement on the end of a connecting stem 6, said enlargement being provided to facilitate the grasping of the handle by the bartender.

In accordance with the present invention I include in the handle or knob formation a flag means that normally does not interfere with the shape or use of the handle, but which is operable to be extended from the handle whenever appropriate, to signify the exhaustion of the keg with which the dispensing valve is associated. To this end, in the illustrated example, I form rigid with the inner surface of the body 5, and at the upper end of the body, the depending ear 10 formed with the opening 10'. Said ear extends inwardly within the body 5, adjacent one end of an elongated narrow slot 11 formed in the body 5 adjacent the flange 8 thereof, and parallel to said flange and to the panel 9 gripped by the flange. The slot 11, as seen from Fig. 2, extends in the present instance through slightly more than half the circumference of the body 5, one end of the slot being designated 12 and the other end being designated 13. At the lower end 13 of the slot 11, the slot is widened to define a notch 14 (Fig. 3).

Normally recessed entirely within the body 5, but adapted to swing into and out of the slot 11, is a flag 15 here shown as formed to a circular shape to correspond to the general configuration of the body 5, said flag being fashioned in the present instance from a thin blank of metal material. The flag can be, and preferably is, marked with any suitable legend 16 to be visually observed by the bartender when the flag is in the uppermost dotted line position illustrated in Fig. 2, the legend in the present instance reading "Out" and signifying that the particular dispensing valve is connected to a keg of beer which has "blown."

Formed in the flag 15 is an opening 17 adapted to be placed in register with the opening 10', rivet 18 or other suitable pivot member extending through said openings for the purpose of pivotally connecting the flag 15 to the ear 10 of the body 5.

In this connection, surrounding the rivet 18 is a cone spring 19, that is interposed between the ear 10 and the flag 15, said cone spring 19 having one end projected as a finger through a small opening 21 formed in the ear 10 adjacent the opening 10' thereof and having its other end extending away from the rivet 18 a suitable distance and outturned to provide a finger 22 that is positioned in small opening 23 spaced from the opening 17 of the flag 15.

The marginal portion of the flag member 15 disposed remote from its pivotal connection to the ear 10, is formed with an offset tongue 24 receivable in the offset notch 14 of the slot 11. In this connection, the cone spring 19 is compressed almost flat between the flag 15 and the ear 10, as readily seen from Fig. 1, so that tending to expand under this axial load, it normally presses the flag member 15 outwardly so as to retain the offset tongue 24 in engagement with the notch 14. As a result, the flag 15 is normally and releasably locked in its inoperative or recessed position shown in full lines in Fig. 2.

Assuming that a keg "blows," the bartender, to prevent anyone including himself from drawing from the tap thereafter, simply presses the tongue 24 out of the notch 14. In other words, the bartender will press the tongue 24 to the right in Figs. 1 or 3.

As a result, the cone spring is now free to unwind, and flips the flag 15 to the uppermost dotted line position shown in Fig. 2. The end 12 of the slot, as will be seen, comprises a stop limiting movement of the flag 15, so that the flag in the present instance extends straight upwardly

from the knob, thus not only to be clearly seen by the bartender, but also to present an obstruction to the bartender's hand if he inadvertently grasps the handle while his attention is distracted.

When a keg is tapped, the bartender simply grasps the flag 15 and returns it to its recessed position with the tongue 24 slipping into the notch 14.

In its basic aspects, the invention is considered to reside in the provision of a signal device built into the knob or handle of a beer dispensing valve and operable for movement to extreme positions in one of which it constitutes a distinct projection signifying an exhausted condition of the keg, and in the other extreme position, presenting no interference to normal use of the handle. Within the claims, it is thought that there are various ways in which the invention can be carried out, the illustrated construction comprising a presently preferred example. I believe, for example, that in some situations the display panel 9 itself might be spring hinged to provide a signal flag. In other instances the flag 15 instead of being rotatably mounted around the pivot, might be mounted for sliding reciprocating movement.

What is claimed is:

1. In a dispensing valve handle a body adapted for connection to the operating rod of a dispensing valve, said body having a slot extending through part of its circumference, a flag normally recessed within the body, a pivotal connection between one end of the flag and the body, said slot being widened at one end to provide a detaining notch, an offset tongue on the flag receivable in said notch to hold the flag in its recessed position, and a cone spring engaged at opposite ends with the body and flag respectively and compressed between said body and flag to press the flag in a direction to hold the tongue within the notch, said cone spring adapted, when the tongue is moved out of the notch, to swing the flag on its pivotal connection outwardly through the slot to provide a projecting signal.
2. In a dispensing valve handle a body adapted for connection to the operating rod of a dispensing valve, said body having an elongated slot extending through a substantial part of its circumference, a flag normally recessed within the body and constituting a signal, a pivotal connection between one end of the flag and the body, said slot having at one end a widened portion to provide a detent notch, a tongue on the flag normally received in said notch to hold the flag recessed within the body, the other end of the slot providing a stop limiting movement of the flag when the flag is swung to a position in which it extends out of the body to provide a signal, and a cone spring wound around the pivotal connection and normally compressed between the flag and body and held under tension, said cone spring being connected at opposite ends to the body and flag respectively, whereby on movement by an operator of the tongue out of the notch, said spring will deflect the flag laterally and outwardly through the slot to swing it to extended position, said spring pressing against the recessed flag to normally hold the tongue engaged within the notch.
3. In a dispensing valve handle a body adapted for connection to the operating rod of a dispensing valve, said body having a slot formed with a widened portion to provide a detaining notch, a flag member pivotally connected to the body to swing into and out of the slot, said flag

member being normally recessed within the slot, a projection on the flag member engageable with the notch in the recessed position of the flag member, and a coiled spring wound around the pivotal connection of the flag member to the body and engaged at opposite ends with the body and flag member, the convolutions of the spring being compressed between the body and flag member to press the flag in a direction to hold the projection normally engaged in the notch, said spring being under tension in the recessed position of the flag member, for swinging of the flag member outwardly through the slot on disengagement of the projection.
